LADY'S GARMENT

Pearl Block Kovitz, New York, N. Y., assignor of
one-half to Samuel J. Goldfarb, New York,
N. Y.

Application April 10, 1943, Serial No. 482,521

2 Claims. (Cl. 2—48)

This invention relates to new and useful improvements in an apron and the like garments.

More particularly, the invention proposes a new apron which is characterized by an arcuately shaped wrap-around skirt portion and a waist portion of a particular construction.

More specifically, it is proposed to characterize the waist portion by a pair of side panels, each of which is in the form of a panel strip attached at its front bottom edge to the central front portion of the skirt portion and extending obliquely upwards and outwards for engaging over one's shoulder and down the back and at its back bottom edge being attached to the adjacent top end portion of said skirt portion. It is proposed that the shoulder portions be provided with an arm opening. It is further proposed that the outer edge of each panel strip at the front be folded into a dart which is stitched down, and which dart extends from the top of the waist portion to the bust areas of the panels, giving fullness to the waist portion of the garment.

The invention further contemplates the provision of means for holding the apron closed when worn.

Still further the invention proposes a new blank or pattern for guiding the cutting of the side panels of the waist portion of the garment.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an illustration of a person wearing an apron or the like garment constructed in accordance with this invention.

Fig. 2 is a rear elevational view of Fig. 1.

Fig. 3 is a developed view of the apron in an open condition.

Fig. 4 is a horizontal sectional view taken on the line 4—4 of Fig. 1.

Fig. 5 is a horizontal sectional view taken on the line 5—5 of Fig. 1.

Fig. 6 is a developed view of one of the side panels of the waist portion of the apron.

Fig. 7 is a fragmentary sectional view taken on the line 7—7 of Fig. 6.

The new apron and the like garment, in accordance with this invention, includes an arcuately shaped wrap-around skirt portion 10 (see particularly Fig. 3) and a waist portion 11 attached upon the top edge of said skirt portion.

The waist portion includes a pair of side panels 12. Each of these side panels 12 is formed from a panel strip attached at its front bottom edge 13 upon the central front top portion of the skirt 10. Each panel strip 12 extends obliquely upwards for engaging over one's shoulder, as illustrated in Fig. 1, and down the back. Each panel strip 12 has its back bottom edge 14 attached to the adjacent top edge portion of the skirt portion 10. Each panel 12 has its shoulder portion formed with an arm opening 15.

An important feature of each side panel resides in the construction of its outer edge 16. The outer edge 16 of each panel strip, at the front of the garment, is folded into a dart 17 which extends from the top of the waist portion of the garment to the bust area of the panel. A small line of stitches 18 holds each dart 17 closed. A feature of the waist portion resides in the fact that the garment has side openings 19 between the top portion of the skirt 10 and the adjacent portions of the side panels.

The garment may be finished with tape trimming 20 sewed along the edges thereof. The skirt portion 10 is provided with a pair of spaced buttons 21 at the back at one side of the skirt portion cooperative with complementary button holes 22 located at the other side of the skirt portion. The garment is shown in a closed position in Fig. 2, while Fig. 3 shows it fully open and spread out. A pair of pockets 23 is mounted upon the front of the skirt portion 10 of the garment.

Fig. 6 is a detail of the pattern used for cutting one of the side panels of the waist portion of the garment, or this figure may be viewed as representing the cut side panel before the parts thereof are sewed together. It should be noted that this pattern or side panel is in the form of a panel strip having the bottom edge 13, from which the strip extends upwards at an oblique angle to the shoulder area 12. In Fig. 6 the shoulder area 12 is shown cut open and flattened out, but it should be visualized that the strip really continues down the back of the garment. The arm opening is represented by the curved portion 15'.

The portion beneath the arm is indicated by the reference numeral 25. The bottom back edge of the strip is indicated by reference numeral 14. A feature of the side panel resides in the fact that the outer edge 16' of the panel strip at the front is folded into a dart 17' which extends from the bottom edge 13 upwards to the bust area of the panel. A line of stitches 18' is schematically in-

dicated for holding the darts 17' closed. The dot and dash line 13' indicates the pattern or panel strip as it would appear before the dart 17 is folded.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In an apron and the like garment having an arcuately shaped wrap-around skirt portion and a waist portion attached to the top edge of said skirt portion, said waist portion being formed of separate side panels each consisting of a panel strip attached at its front bottom edge to the central front portion of said skirt portion and having openings disposed intermediate the top portion of said skirt and the adjacent portions

10 of said side panels, each of said panel strips being extended obliquely upwards for engaging over one's shoulder and down the back and having the bottom edge of its back portion attached to the adjacent top end portion of said skirt portion, and a dart formed in the outer edge of the front portion of said panel strip and extending from the top of the waist portion to the bust area of the panel.

5 2. In an apron, a waist portion formed of separate side panels each of which consist of a panel strip having its free front bottom edge extended to a point adjacent the waist of the wearer, each of said panel strips extending obliquely upwardly from said point and engaging over the shoulder and down the wearer's back and terminating at a point adjacent the waist of the wearer, means at the waist of the wearer for securing said strips at said points, said waist portion having openings disposed intermediate said means and the adjacent portions of said panels.

PEARL BLOCK KOVITZ.
